EYELASH CURLER

Louis Eisenman, Brooklyn, N. Y.

Application September 16, 1936, Serial No. 101,167

10 Claims. (Cl. 132—32)

This invention relates to eyelash curlers. Various attempts have been made to provide manually actuated devices for curling eyelashes. The majority of such devices now on the market involve a movable member adapted to engage and press against a fixed member in the same plane and to squeeze the eyelashes between the engaging edges or parts. The operation of such devices necessitated a pressing operation and a releasing operation and frequently involves actuating mechanism impractically and inconveniently arranged with respect to the other operating parts and the face of the user while the device was being operated.

It is therefore one of the objects of the present invention to provide a simple and practical eyelash curler adapted to overcome the objections experienced heretofore with similar devices.

A further object is to provide an improved eyelash curler in which the lashes will be curled by a single pressing operation and automatically released at the end of the pressing stroke or actuating movement.

A further object is to provide an eyelash curler of the above character, which will be safe and reliable and efficient, and one which will in no way injure the eyelid during operation or have movable parts annoyingly engaging the face of the user during operation.

A further object is to provide an eyelash curler of the above general character having relatively few parts which may be inexpensively manufactured and assembled.

A further object is to provide a device of the above character, which may be easily and quickly adjusted to the length of the eyelashes to be curled.

Other objects will be in part obvious from the annexed drawing and in part hereinafter indicated in connection therewith by the following analysis of this invention.

This invention accordingly consists in the features of construction, combination of parts, the unique relation of the members, and in the relative proportioning and disposition thereof, all as more completely outlined herein.

To enable others skilled in the art to fully comprehend the underlying features of the invention, that they may embody the same by the numerous modifications in structure and relation contemplated by the invention, a drawing depicting a preferred form has been annexed as part of this disclosure, and in such drawing like characters of reference denote corresponding parts throughout the views, in which—

Fig. 1 is an elevational front view showing the complete device;

Fig. 2 is a sectional view taken substantially at right angles to Fig. 1;

Fig. 3 is a detail end or plan view; and

Fig. 4 is a detail view of one of the parts.

Referring now to the drawing in detail, and more particularly to Fig. 1, 5 indicates the main frame or supporting handle which is adapted to occupy a relatively fixed position with respect to the face when the device is in use. This portion 5 comprises a substantially cylindrical tubular portion, an upper offset portion 6 at right angles thereto extending towards the face just above the cheek-bone when in use, and a second offset 15 member 7 at right angles thereto adapted to engage the face just below the lower eyelid. This member 7 is bifurcated at 8, that is, it extends laterally to each side for a total width approximately equal to the width of the eyelids.

Upwardly extending side portions 10 are connected at their tops by a curved arcuate portion 11 adapted to rest on the outer surface of the upper eyelid, just above the eyelashes. This member is approximately $\frac{3}{8}$ inch wide, and the lower edge 12 is positioned just above the eyelashes, so that they normally curl upwardly and outwardly in front of this portion 11 when in use. The outer surface of part 11, as indicated at 13, may be provided with one or more ridges upon which dye or any desired color is adapted to be placed when it is sought to color or tint the eyelashes.

At each side of the uprights 10 there are provided elongated slotted guides 14, the slot being approximately $\frac{3}{4}$ inch in length and in which are adapted to travel guide pins 15 mounted upon each side of a movable frame. This frame comprises a rod-like member 16 adjustably threaded into a bottom cap 17 of generally cylindrical shape as shown at the bottom of Fig. 1, thus providing a chamber 18 for housing a spring 20 coiled about the lower end of the part or rod 16 and adapted to be compressed as the cap 17 is forced upwardly towards the stop 19 on the telescoping section 21 of the main body part 5. The upper end of this rod 16 is provided with an offset portion 22 substantially coextensive with the part 6, and at right angles thereto is a second offset portion 23 engaging the part 7. The upper end part 23 is bifurcated as indicated at 24 and carries the pins 15 traveling in the slotted guides 14 and a transverse member 25 extending between pins 15. This member 25 is cut as indicated at 26, whereby a tubular rubber presser 27

may be mounted thereon by separating the part 25 at its cut portion 26, threading on the tube 27, and then allowing it to expand so as to extend completely between the guides 14, as shown. This 5 member 25, as shown more clearly in Figs. 3 and 4, is curved substantially in accordance with the curvature of the part 11. I prefer to have the rubber presser 27 on the part 25 as shown, rather than on the dye carrying surface 13, although 10 this reversal may be made if desired.

It will be thus seen that when operating the device it is grasped between the first finger engaging a ring 28 and the thumb engaging the cap 17 and, by pressing the thumb towards the finger, 15 the rod 16 is moved upwardly against the action of spring 20 the desired adjusted amount, thereby to move the rubber presser 27 upwardly with respect to the member 11 and in a plane parallel thereto. When this pressure is released, the 20 spring 20 restores the parts to the position shown in Fig. 1. During this operation it may be assumed that the device is placed in operative relation to the eyelashes to be curled, that is, the part 11 is pressed against the upper eyelid with 25 the lashes projecting under the edge 12. Then as the presser 27 moves upwardly the eyelashes are pressed between the parts 13, which may be coated with coloring matter, and the rubber 27. This gentle upward pressure causes the eyelashes 30 to curl upwardly and to be tinted at the same time.

It will be noted particularly that with this wiping, pressing action, as distinguished from devices heretofore in use, in which an edge directly abuts 35 against and into a concave rubber surface in the same plane, injury to the eyelid itself is prevented. In other words, there is no danger of actually pressing the lower edge of the eyelid as has heretofore been experienced. Furthermore, at the 40 extreme end of the upward relative movement of the presser 27, the eyelashes are automatically released, thus doing away with the return operation heretofore required. If the lashes are unusually long, the stroke may be increased by the 45 cap 17. Of course as soon as pressure on the button or cap 17 is released, the parts automatically return to normal position but not while in engagement with the lashes. Furthermore, by having the actuating parts arranged in a substantially straight vertical line, the annoyance of 50 moving parts towards and from the face is eliminated.

It is thus seen that the present invention comprises a simple and practical eyelash curler which 55 will be safe, efficient, and reliable in use and operation. The device comprises relatively few parts which may be inexpensively manufactured and assembled and which is well adapted to accomplish, among others, all of the objects and 60 advantages herein set forth.

Without further analysis the foregoing will so fully reveal the gist of the invention that others can by applying current knowledge readily adapt it for various applications without omitting certain features that from the standpoint of the prior art fairly constitute essential characteristics of the generic or specific aspects of this invention, and therefore such adaptations should and are intended to be comprehended within the meaning and range of equivalency of the following 65 claims.

I claim:—

1. An eyelash curler comprising a relatively 70 stationary member having a tubular handle portion, a movable member having a rod telescopic-

ing said handle, and resilient means for holding said members in normal position, means for moving one member with respect to the other, a relatively fixed eyelid engaging portion, a relatively movable eyelash engaging portion movable thereon and connected respectively with the stationary and movable parts of the body portion and spring means adapted to connect the relatively stationary member and movable parts to restore said parts to normal position after operation. 10

2. An eyelash curler comprising a relatively stationary member having a tubular handle portion, a movable member having a rod telescoping said handle, and resilient means for holding said members in normal position, means for moving one member with respect to the other, a relatively fixed eyelid engaging portion, and a relatively movable eyelash engaging portion connected respectively with the stationary and movable parts of the body portion, said movable portion adapted 1 to move over the outer surface of said fixed portion and to press the eyelashes therebetween and automatically release the eyelashes at the end of the stroke. 1

3. An eyelash curler comprising a relatively stationary member having a tubular handle portion, a movable member having a rod telescoping said handle, and resilient means for holding said members in normal position, means for moving one member with respect to the other, a relatively fixed eyelid engaging portion and a relatively movable eyelash engaging portion connected respectively with the fixed and movable parts of the body portion, the relative range of movement of said last-mentioned fixed and movable parts 3 being greater than the normal length of the eyelashes, thereby to automatically release the eyelashes at the end of the stroke. 3

4. An eyelash curler comprising a relatively fixed frame having a handle portion and an eyelid engaging portion, and a relatively movable frame telescopically carried by the handle portion and having a portion adapted to coact with the eyelid engaging portion to press the eyelashes therebetween with a wiping action as it passes 4 bodily thereover, one of said eyelash engaging surfaces being rubber-coated, and the other surface being provided with a rib adapted to carry coloring matter for tinting the eyelashes. 4

5. An eyelash curler of the character described 5 comprising a main frame adapted to have a normally fixed operative position, a movable frame telescopically positioned with respect thereto and substantially coextensive therewith, spring means acting between the telescoping parts for restoring the same to normal position after operation, the upper part of the fixed frame having a curvature conforming to the curvature of the eyeball, guides at the sides thereof, the movable frame having a part curved to correspond to the 6 curvature of the first curved part and being guided in its movement by said guides, said movable part being positioned substantially parallel to the fixed part and adapted to have a wiping action thereover thereby to press the eyelashes 6 between the fixed part and the movable part. 6

6. An eyelash curler of the character described 7 comprising a main frame adapted to have a normally fixed operative position, a movable frame telescopically positioned with respect thereto and substantially coextensive therewith, means adjusting the extent of telescopic movement the upper part of the fixed frame having a curvature conforming to the curvature of the eyeball, guides at the sides thereof, the movable frame having a 7

part curved to correspond to the curvature of the first curved part and being guided in its movement by said guides, said movable part being positioned substantially parallel to the fixed part 5 and adapted to having a wiping action thereover thereby to press the eyelashes between the fixed part and the movable part, one of said parts being rubber-coated and the other of said parts being adapted to carry an eyelash tint.

10 7. An eyelash curler comprising a relatively fixed frame having a handle portion and an eyelid engaging portion, and a relatively movable frame telescopically carried by the handle portion and having a portion adapted to coact with 15 the eyelid engaging portion to press the eyelashes therebetween with a wiping action as it passes bodily thereover, and means for adjusting the extent of telescoping movement whereby the lashes are automatically released at the end 20 of the wiping action.

8. An eyelash curler comprising a curved plain member adapted to be laid against the outer surface of an eyelid, and a member adapted to be moved bodily over the exposed surface of said 25 member and to press the eyelash against the exposed outer surface by a wiping action between the two relatively moving parts, the extent of movement of one surface over the other being in excess of the normal length of the eyelash, 30 thereby automatically to release the eyelash at the end of the wiping action.

9. An eyelash curler comprising a curved plain member adapted to be laid against the outer surface of an eyelid, and a member adapted to be moved bodily over the exposed surface of said member and to press the eyelash against the exposed outer surface by a wiping action between the two relatively moving parts, the extent of movement of one surface over the other being in excess of the normal length of the eyelash, 5 thereby automatically to release the eyelash at 10 the end of the wiping action, and spring means operating between the two relatively movable parts adapted to restore the same to normal position.

10. An eyelash curler comprising a curved plain member adapted to be laid against the outer surface of an eyelid, and a member adapted to be moved bodily over the exposed surface of said member and to press the eyelash against the exposed outer surface by a wiping action between 15 the two relatively moving parts, the extent of movement of one surface over the other being in excess of the normal length of the eyelash, thereby automatically to release the eyelash at the end 20 of the wiping action, the exposed outer surface 25 of said first member being irregularly shaped to receive and retain a dye, whereby the eyelashes may be tinted during the wiping action.
